DUST SUCTION DEVICE FOR CLEANING
FURS, CLOTHING, ETC.

Stephen Lányi, Passaic Park, N. J.

Application June 27, 1935, Serial No. 28,600

2 Claims. (Cl. 15—6)

This invention relates to new and useful improvements in a dust suction device for cleaning furs, clothing, etc.

The invention has for an object the construction of a device as mentioned which is characterized by a casing substantially of inverted, saucer-like shape and having a longitudinal slot in its top over which the furs, clothing and the like may be passed during the cleaning operation.

10 More particularly, the invention contemplates the provision of an air duct within the casing for extending over said slot and connected with a vacuum dust collector bag, and an arrangement for blowing or sucking the dust into said bag.

15 Still further the invention proposes the provision of a rotary brush extended across said longitudinal opening and adapted to engage against the fur and clothing moved over the opening to brush the dust therefrom.

20 Furthermore, the invention proposes the provision of an element or elements upon the brush adapted to strike against the metal or material at the sides of the longitudinal opening or upon other material in the vicinity thereof to assist in better shaking the dust from the furs or clothing.

25 A further object of this invention is the arrangement of a porous wire mesh material extended over the opening so as to prevent buttons and other small parts from the clothing engaging therein, but arranged in such a manner as not to interfere with the proper operation of the device.

Another object of the invention is the construction of a device as described which is simple and durable and which may be manufactured and sold at a reasonable cost.

30 For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:—

45 Fig. 1 is a plan view of a device constructed according to this invention.

Fig. 2 is a perspective view of the device shown in Fig. 1.

Fig. 3 is a bottom elevational view of Fig. 1.

50 Fig. 4 is a sectional view taken on the line 4—4 of Fig. 1.

Fig. 5 is a sectional view taken on the line 5—5 of Fig. 4.

55 Fig. 6 is a fragmentary horizontal sectional view taken on the line 6—6 of Fig. 4.

The dust suction device for furs, clothing, etc., according to this invention, includes an inverted, saucer-like casing 10 adapted to be attached upon a table 11 and formed with a longitudinal slot 12 in its top. An air duct 13 is arranged within the casing 10 and extends over the opening 12 and connects with a vacuum dust collector bag 14. A blower 15 is arranged within the casing 10 and is connected with the duct 13 so as to create suction at the slot 12, and to discharge air drawn in through the slot into the bag.

A combination brush and vibrator 16 is arranged with the duct 13 immediately adjacent the slot 12 for brushing and beating the furs, clothing, etc. which are drawn or passed over the top opening in the casing.

The casing 10 has several curved side portions 10^a, 10^b, etc. and a comparatively flat top portion 10^c. Screen material 17 is mounted on the flat portion 10^c and is adapted to cover the opening 12. This screen material is formed with a bulged portion (see Fig. 4) so as to better accommodate the brush 13. The material 17 is held removably in position by the provision of several pegs 18 mounted thereon and engaging in receiving openings in the top portion 10^c of the casing.

20 The air duct 13 in the vicinity of the slot 12 is of sufficient compass to encase the slot. It then decreases in compass until the discharge end 13^a, which is substantially of cylindrical form. The 30 dust bag 14 is adapted to have its neck engaged on the discharge portion 13^a. The blower 15 is mounted in the wall of the casing and has its air discharge 15^a arranged at an angle to the side wall of the duct 13 so as to blow through the duct 35 and cause suction at the slot (12) end of the duct.

The brush 16 is driven by an electric motor 20 which is mounted upon the wall of the casing. This electric motor is connected by a belt or chain 21 with a pulley 22 upon a shaft 23 of the brush 40

16. The shaft 23 has another pulley 24 at its other end which is connected by a belt or chain 25 with the blower 15 so as to drive the blower during the operation of the brush. The table 11 is formed with openings 11^a over which the casing 10 extends. The duct 13 extends through this opening and connects with the bag 14, which is located beneath the table.

45 The combination brush and vibrator comprises a central hub portion 16^a from which bristles 16^b project. These bristles are arranged in groups spaced from each other, and between these groups there are vibration elements. Each vibration element consists of a longitudinally extending metallic impact member 16^c or members ra- 50 55

dially slidably supported and limited against complete displacement by headed studs 16^d which are mounted upon the hub 16. Springs 16^e resiliently urge the impact members 16^c into extended 5 positions.

The outer ends of the members 16^c are tapered, as clearly shown in Fig. 4, so that the sides thereof act as cam surfaces in forcing the retraction of these members when they engage resisting 10 parts. These resisting parts consist of the material of the casing 10 adjacent the sides of the opening 12 on the screen member 17.

As the combination brush and vibrator 16 operates the bristles extend through the openings in the member 17 and brush the dust from the fur, clothing, and like. Simultaneously, the fur, clothing and like is subjected to a beating operation indirectly by the impact members 16^c causing vibration of the member 17. The dust which 20 is freed from the fur will be drawn inwards by the suction created by the blower 15.

The shaft 23 has a removable section 23^a which is releasably held by couplings 23^b. It is possible to disconnect the couplings 23^b so as to remove 25 the brush 16. It may then be replaced by another type of brush, or the identical brush repaired, cleaned, etc.

A speed control arm 20' of the motor 20 is projecting through slot 10^d of the casing 10. The motor may be connected to the usual A. C. or 30 D. C. supply by a connecting plug or the like.

While I have illustrated and described the preferred embodiment of my invention, it is to be understood that I do not limit myself to the precise construction herein disclosed and the right is reserved to all changes and modifications coming 35 within the scope of the invention as defined in the appended claims.

Having thus described my invention, what I

claim as new, and desire to secure by United States Letters Patent is:

1. A dust suction device for furs, clothing, etc., comprising an inverted saucer-like casing adapted to be attached on a table and having a longitudinal slot in its top, an air duct within the casing and extending below said slot, a blower connected with said duct so as to create suction at the slot and to discharge air drawn in through the slot, and a combination brush and vibrator 5 within the duct and adjacent said slot for brushing and beating furs, clothing, etc., passed over the top of said casing, said casing having several curved sides and a flat top to facilitate the sliding of furs, clothing, etc. thereover, and a screen 15 member being removably mounted upon said flat top for covering said slot to prevent buttons and the like from projecting into the casing.

2. A dust suction device for furs, clothing, etc., comprising an inverted saucer-like casing adapted to be attached on a table and having a longitudinal slot in its top, an air duct within the casing and extending below said slot, a blower connected with said duct so as to create suction at the slot and to discharge air drawn in through 20 the slot, and a combination brush and vibrator within the duct and adjacent said slot for brushing and beating furs, clothing, etc., passed over the top of said casing, said casing having several curved sides and a flat top to facilitate the sliding 25 of furs, clothing, etc. thereover, and a screen member being removably mounted upon said flat top for covering said slot to prevent buttons and the like from projecting into the casing, said cover material having a curved portion to accommodate 30 the curvature of the combination brush and vibrator.

STEPHEN LÁNYI.
